ELECTROACOUSTICAL TRANSDUCER

Robert Adler, Northfield, Ill., assignor to Zenith Radio Corporation, a corporation of Delaware

Application May 24, 1957, Serial No. 661,348

6 Claims. (Cl. 179—111)

This invention relates generally to electroacoustical transducers and more particularly to a new and improved condenser microphone of simple and economical construction and having substantially greater sensitivity than has heretofore been possible.

As is well known, maximum power is extracted from a generator when the load impedance is a conjugate of the generator impedance. However, in order to secure a maximum transfer of energy between two connecting networks, if the respective phase angles of the two networks are not adjustable, the absolute value of the impedance of one should be equal to the absolute value of the impedance of the other.

Air, like any other medium capable of carrying waves, can be assigned an acoustical characteristic impedance which is defined as the quotient of the pressure by the particle velocity in a sound wave. Similar to the reactance of a coil to alternating current, a microphone diaphragm has a resistance to alternating motion which can be expressed in terms of a resonant impedance, sometimes referred to as its mechanical impedance, indicative of the molecular friction or damping loss within the diaphragm. The resonant impedances of the diaphragms of most conventional microphones, whether of condenser, piezoelectric or crystal, magnetic, or magnetostrictive type, are generally several times larger than the acoustical characteristic impedance of air. Consequently, it is desirable to provide some means for matching these two impedances to insure a transformation of all of the acoustical energy into the desired electrical energy so that maximum sensitivity of the microphone is attained.

It is also generally desirable to provide the microphone structure with a protective enclosure in order to isolate the diaphragm and other delicately constructed components from the deleterious effects of dust, moisture, and the like, and in addition, to provide some degree of protection from physical abuse. Such enclosures normally include a faceplate including a grille which is apertured to permit passage of the sound waves to be intercepted by the diaphragm. The grille, however, creates a partial obstruction to the incoming sound waves and thus may cause an additional decrease in the sensitivity of the microphone.

Therefore one of the principal objects of this invention is to devise a new and improved microphone which utilizes a unique apertured grille without adversely affecting the sensitivity of the microphone.

Another object of the invention is to device a new and improved microphone which utilizes an apertured grille in a novel manner to provide a substantial match between the acoustical characteristic impedance of air and the resonant impedance of the diaphragm, whereby the sensitivity of the microphone is substantially increased.

A further object of this invention is to devise a new and improved condenser microphone which is relatively simple, economical, trouble free, and readily adaptable to mass production techniques.

2

Another object of this invention is to devise such a new and improved condenser microphone having a higher sensitivity than heretofore possible.

In accordance with one aspect of the present invention, there has been devised a new and improved microphone comprising a vibratile diaphragm resonant at a predetermined frequency of incident sound vibrations and having a predetermined mechanical impedance at its resonant frequency. Means are provided for substantially matching the mechanical impedance of the diaphragm with the acoustical impedance of air. These means include a faceplate including a multi-apertured grille parallel to the diaphragm and spaced therefrom by a distance substantially equal to

$$\frac{m\lambda}{2}$$

and establishing an otherwise substantially closed acoustical cavity therebetween. The grille has at least one characteristic dimension which is greater than $\lambda/2$ and a thickness substantially equal to

$$\frac{2n-1}{4}\lambda$$

25 The spacing between the peripheries of adjacent apertures in the grille is less than $\lambda/2$ and the grille has a percentage aggregate perforate area with respect to its total surface area substantially equal to

$$\sqrt{\frac{Za}{Zd}} \times 100\%$$

where Za is the acoustical impedance of air, Zd is the mechanical impedance of the diaphragm, λ is the wave length of the resonant sound vibrations in air, and m and n are integers.

In accordance with another aspect of the present invention, there has been devised a new and improved condenser microphone having a predetermined acoustical resonant frequency. The microphone comprises an insulating support member having a substantially flat surface and a metallic stationary plate member imbedded in the support member. The stationary plate member has a substantially flat exposed surface coplanar with the surface of the support member. A frame-shaped

40 spacer member is provided having two oppositely disposed substantially parallel surfaces and having a thickness which is at least one order of magnitude smaller than the wave length in air corresponding to the resonant frequency of the microphone. The spacer is in surface contact with the support member and substantially encompasses the exposed surface of the stationary plate member; the shortest distance between the spacer and the stationary plate member is substantially greater than the spacer thickness. There is also provided a vibratile

45 membrane having a substantially uniform thickness which is at least two orders of magnitude smaller than the wave length corresponding to the resonant frequency of the microphone in air. The membrane is in surface contact with the opposite surface of the spacer than the support member, is substantially taut, and is parallel to the exposed surface of the plate to form a substantially uniform and closed acoustic chamber therebetween. One of the characteristic dimensions of the chamber is thus equal to the thickness of the spacer and, along with the distributed mass of the membrane, determines the resonant frequency of the microphone. The membrane is stressed by an amount only to insure tautness but not by an amount sufficient to substantially affect the resonant frequency.

50 55 60 65 70 The features of the present invention which are believed to be novel are set forth with particularity in the appended claims. The organization and manner of op-

eration of the invention, together with further objects and advantages thereof, may best be understood by reference to the following description taken in connection with the accompanying drawing, in the several figures of which like reference numerals identify like elements, and in which:

Figure 1 is an elevational view of a microphone constructed in accordance with the present invention;

Figure 2 is a cross-sectional view of the microphone as viewed along the line 2—2 of Figure 1;

Figure 3 is a cross-sectional view of the microphone as viewed along the line 3—3 of Figure 1; and

Figure 4 is an exploded view of the microphone assembly.

For some applications, it may be desirable to provide a diaphragm resonant frequency slightly higher than the frequency of intended use of the microphone. The sensitivity of a condenser microphone increases rapidly as the thickness of the air cushion behind the diaphragm decreases, and the resonant frequency of the diaphragm varies directly with the square root of the density of the air. Thus, if the microphone is operated in a locality of substantially reduced barometric pressure, the resonant frequency of the microphone is reduced to a value in the region of the frequency of intended use. As a result, the sensitivity of the microphone does not decrease, but is maintained constant or may even increase somewhat when operated in a locality of lower barometric pressure. In this manner, maximum utility, regardless of geographical location, may be obtained. The invention is described with particular reference to an ultrasonic microphone for use in conjunction with a remote control system operating at about 40 kilocycles, and the resonant frequency of the diaphragm is established at 45 kilocycles.

With reference to the drawings, a microphone constructed in accordance with the present invention comprises an insulating support 10 having a substantially flat and smooth surface 11 formed on one side thereof. A metallic and substantially rectangular-shaped plate electrode 12 is embedded in support 10 and is held in position by cement or other suitable means. Electrode 12 is provided with a substantially flat and smooth surface 13 which is coplanar with face 11 of support 10. A metallic and substantially rectangular frame-shaped spacer 14 is in surface contact with face 11 of support 10 and completely encompasses, yet is electrically insulated from, the exposed surface of electrode 12. For reasons to be more apparent hereinafter, spacer 14 is provided with flat and smooth oppositely-disposed parallel surfaces, one of which is in contact with support 10. A metallic-coated vibratile plastic membrane 15 is in surface contact with the exposed surface of spacer 14. Membrane 15 is tautly stretched across spacer 14 to insure a parallel relationship thereof with respect to the exposed face of electrode 12 but is not maintained under sufficient lateral stress to materially affect its resonant frequency. An acoustic cavity is thus formed between membrane 15 and electrode 12. A metallic gasket 16 and a plastic gasket 17, each of uniform thickness, are placed in juxtaposition with the exposed side of diaphragm 15, and the entire assembly is held together by means of a spring pressure plate 18 which is mechanically connected to face plate 19 by a pair of screws 20. The maximum pressure exerted by plate 18 on the assembly is determined by tubular spacer members 21 interposed between pressure plate 18 and face plate 19 and surrounding screws 20. The entire assembly is held in proper alignment by dowel pins 22 press-fitted into face plate 19 and cooperating with suitable indexing holes 23 (Figure 4) formed in the various elements.

Face plate 19 includes a rectangular-shaped grille, shown more clearly in Figure 1 as dotted line 24, having substantially smooth oppositely disposed parallel faces and further having a uniform thickness t as shown in Figure 3. Grille 24 is provided with a plurality of paral-

lal rectangular-shaped slots 25, each having a length l and a width w , as indicated in Figure 1. Slots 25 preferably extend for the full width of grille 24 and are equally spaced from one another to form a slot pattern which is centrally disposed with respect to grille 24. As shown in Figure 3, grille 24 is parallel to diaphragm 15 and is spaced therefrom by a distance d . Face plate 19 is provided with a rectangular cavity 26 to establish an otherwise closed and uniform acoustic chamber between grille 24 and diaphragm 15.

As shown in Figure 2, metallic-coated vibratile membrane 15 constitutes one electrode of a variable condenser and is electrically returned to ground potential by conductor 27 connected to spacer 14, which, in turn, is in electrical contact with membrane 15. Fixed electrode 12 is electrically connected to a source of unidirectional operating potential, conventionally designated B_+ , through a resistor R ; electrode 12 may be connected to the input circuit of a suitable amplifier through a coupling condenser (not shown).

In operation, sound waves enter the microphone through slots 25 and impinge upon diaphragm electrode 15 to vary the spacing and hence the capacity between electrodes 12 and 15. This change in capacity is reflected as a corresponding change in voltage developed across resistor R , in a manner fully analogous with the electrical operation of condenser microphones of known construction.

The acoustic system of the illustrated condenser microphone is not, however, quite so simple and will be explained in terms of an example of the actual mechanics involved.

In the design of prior condenser microphones, it has been the general practice to provide a diaphragm electrode spaced from a fixed electrode and laterally stressed by a predetermined amount until the desired resonant frequency of the diaphragm is obtained; in some constructions, the stress imposed may even be of sufficient magnitude to approach the elastic limit of the diaphragm. In a condenser microphone embodying the present invention, diaphragm 15 is tautly stretched across spacer 14 to insure a parallel relationship between diaphragm 15 and fixed plate 12 but is not stressed by an amount to substantially affect the resonant frequency of the diaphragm.

In the preferred construction, diaphragm 15 is composed of a polyester film, such as that manufactured by I. E. du Pont de Nemours and Company and sold under the name of Mylar, provided with an evaporated aluminum film of a thickness sufficient to give a resistance of approximately 10 ohms per square. It has been found that an aluminum coated Mylar diaphragm having a thickness of $1/2$ mil has a mass per unit area sufficient to resonate at approximately 45 kc. with a 4 mil air cushion, an air gap sufficiently large to permit the use of mass production assembly techniques without encountering short circuits and arc-overs.

In order to reduce electrical leakage between diaphragm 15 and electrode 12, spacer 14 is dimensioned so that the shortest distance between spacer 14 and electrode 12, shown as s in Figure 2, is substantially greater than the depth of the air cushion which is equal to the thickness of spacer 14 or 4 mils; in the preferred embodiment the spacing s may be 32 mils.

The acoustical characteristic impedance for air at room temperature is approximately equal to 42 dynes/cm.² per cm./second, while $1/2$ mil thick aluminum-coated Mylar diaphragm utilized by the present microphone has a calculated resonant reactance of approximately 12 times the characteristic impedance of air. Therefore, if there were no friction or damping within the microphone and the diaphragm were simply exposed to open air, its resonant curve would have a "quality factor," commonly designated "Q," of 12; "Q," in this instance, may be defined as the quotient of the resonant impedance of the diaphragm by the characteristic impedance of air. How-

ever, experimental measurements indicate that the microphone in open air, with the face plate removed, has a "Q" of only 3. Thus, it is evident that there exists, somewhere in the microphone structure, a friction or damping loss equivalent to 3 times the characteristic impedance of air, making a total resistance 4 times that which would be expected from air damping alone.

In the microphone of the present invention, face plate 19 and particularly grille 24 are uniquely constructed to provide a substantial impedance match between the acoustical characteristic impedance of air and the resonant impedance of diaphragm 15 to improve the sensitivity of the assembly. The characteristic impedance of the grille increases in inverse proportion to the fractional open area; that is, the characteristic impedance increases as the fractional open area decreases and decreases as the fractional open area increases. The fractional open area of grille 24 is defined as the ratio of the aggregate open area of slots 25 to the total surface area of the grille.

The resonant impedance of the diaphragm is matched with the characteristic impedance of air by providing a grille of a thickness substantially equal to an odd number of one-quarter wavelengths at the operating frequency and having a fractional open area substantially equal to

$$\sqrt{\frac{Z_a}{Z_d}} \times 100\%$$

where Z_a and Z_d are the characteristic impedance of air and the resonant impedance of the diaphragm, respectively. Moreover, grille 24 is spaced from diaphragm 15 by an integral number of one-half wavelengths at the operating frequency; an obviously equivalent construction is one in which the spacing d is made as close to zero as possible without inhibiting vibration of the diaphragm, and this construction is accordingly within the spirit and scope of the invention. In the example shown, the thickness t of grille 24 is substantially equal to one-quarter wave length at the desired operating frequency of 40 kilocycles, or approximately 0.086 inch. The spacing between grille 24 and diaphragm 15 is one-half wavelength at 40 kilocycles, or 0.172 inch. Moreover, as diaphragm 15 has a resonant impedance equal to 3 times the acoustical characteristic impedance of air, the characteristic impedance of grille 24 should be substantially equal to $\sqrt{3}$ times the characteristic impedance of air. Therefore, the maximum opening of grille 24 is reduced to approximately

$$\sqrt{\frac{1}{3}} \times 100\%$$

and the total aggregate open area of slots 23 is substantially 58% of the total surface area of grille 24.

To avoid undesirable phase errors, it is preferred that slots 25 be parallel to and spaced from one another so that the distance between adjacent slots is substantially less than one-half wave-length of sound in air at 40 kc., or 0.172 inch. Slots 25 are preferably rectangular and extend substantially across the entire width of grille 24 as viewed in Figure 1. The slots are also preferably equally spaced from one another and arranged in a pattern which extends substantially the entire length of grille 24.

In utilizing the previously described microphone as a pick-up device, for example in a remote control apparatus such as that shown and described on pages 156-161 of the March 1, 1957, issue of "Electronics," it may be desirable to provide a compromise between the maximum sensitivity and the directivity of the microphone. With the microphone oriented in a position shown in Figure 1 of the drawings, the horizontal directivity is either increased or decreased, as desired, by effecting a corresponding increase or decrease in the width W of the diaphragm. By the same token, the vertical directivity is either increased or decreased, as desired, by effecting a

corresponding increase or decrease in the length L of the diaphragm. The ideal situation would of course exist in the apparatus above mentioned when the microphone possesses the characteristics of maximum sensitivity and minimum directivity; that is, it is desirable that the microphone have a maximum of sensitivity in response to incoming sound vibrations of the control frequency approaching the diaphragm from any and all directions, so that the response is not at all dependant upon the angle of incidence of the impinging sound wave fronts.

However, an increase in either of the characteristic surface dimensions of the diaphragm effects a corresponding increase in sensitivity but also causes the microphone to be more directional which may be undesirable for some applications. In the remote control apparatus mentioned, it is desired to dimension the diaphragm, and consequently the grille of the microphone, so that width W is substantially equal to one wavelength at the operating frequency, or approximately 0.35 inch; length L is dimensioned to be substantially equal to two wavelengths at the operating frequency, or approximately 0.70 inch. As a result, the microphone has a directivity of substantially plus or minus 30° in a vertical direction, and has a directivity of plus or minus 90° in a horizontal direction. It is to be noted, however, an important feature of such a construction is that a change in the width dimension of the diaphragm does not substantially affect the vertical directivity, and conversely, a change in the length dimension of the diaphragm does not substantially affect the horizontal directivity.

Microphones constructed in accordance with the present invention possess many desirable characteristics that have not heretofore been available to the art. Firstly, it is quite evident that surfaces 11 and 13 of support 10 and fixed electrode 12, respectively, are very easily rendered coplanar with respect to one another simply bylapping or otherwise machining the two surfaces simultaneously. Secondly, the depth of the air cushion between diaphragm 15 and electrode 12, and consequently the resonant frequency of the diaphragm for a given distributed mass, is determined simply by the thickness of spacer 14 because diaphragm 15 is lightly stretched across spacer 14 by an amount only to insure straightness thereof but not by an amount to substantially affect its resonant frequency. As a result of its unique construction, the microphone is extremely simple, rugged and economical and yet provides improved sensitivity as compared with prior condenser microphones.

While the invention has been shown and described as embodied in a condenser microphone, the impedance matching arrangement of the invention may be employed with equal or even greater advantage in piezoelectric and other types of microphones, since the impedance mismatch encountered in such other devices is generally greater than that encountered in a condenser microphone.

While a particular embodiment of the invention has been shown and described, it will be obvious to those skilled in the art that changes and modifications may be made without departing from the invention in its broader aspects, and, therefore, the aim in the appended claims is to cover all such changes and modifications as fall within the true spirit and scope of the invention.

I claim:

1. A microphone structure comprising in combination: a vibratile diaphragm resonant at a predetermined frequency of incident sound vibrations and having a predetermined mechanical impedance at said resonant frequency; and means for substantially matching said diaphragm impedance with the acoustical impedance of air, comprising a face plate having a multi-apertured grille parallel to said diaphragm and spaced therefrom by a distance substantially equal to
